Primary Examiner — Jonathan J Han*Assistant Examiner* — Caitlin MacKenzie Williams(74) *Attorney, Agent, or Firm* — Banner & Witcoff, Ltd.(57) **CLAIM**

The ornamental design for a shoe, as shown and described.

DESCRIPTION

FIG. 1 is a front perspective view of a shoe showing our new design;
FIG. 2 is a side view thereof;

FIG. 3 is a rear perspective view thereof;
FIG. 4 is a front perspective view showing an alternative embodiment of my new design;

FIG. 5 is a side view thereof; and,

FIG. 6 is a rear perspective view thereof.

The broken lines immediately adjacent to the shaded area define the bounds of the claimed design and form no part thereof. The broken lines depicting the remainder of the shoe form no part of the claimed design.

1 Claim, 6 Drawing Sheets(56)
